UNITED STATES PATENT OFFICE.

MAXWELL RIDDLE, OF RAVENNA, OHIO.

CENTRIFUGAL NUT-CRACKING MACHINE.

Application filed December 31, 1920. Serial No. 434,384.

To all whom it may concern:

Be it known that I, MAXWELL RIDDLE, a citizen of the United States of America, residing at Ravenna, in the county of Portage and State of Ohio, have invented certain new and useful Improvements in Centrifugal Nut-Cracking Machines, of which the following is a specification.

The primary object of the invention is the provision of a machine for easily and quickly cracking nuts such as palm nuts, the operation being also capable of removing the husks from the nuts.

A further object of the invention is the provision of a machine for husking nuts when operated at one speed and cracking them by increasing the speed of the machine, the operation in either event involving centrifugal action and means for preventing 20 the clogging of the machine during operation.

A still further object of the invention is the provision of a centrifugal nut cracker operating on a horizontal axis whereby the radial projecting of the nuts against a breaking wall performs the cracking operation, the cracked nuts being adapted to leave the machine by the force of gravity.

With these general objects in view, the invention consists of the novel form, combination and arrangement of parts herein-after more fully described in connection with the accompanying drawings, in which like reference characters designate corresponding parts throughout the several views.

In the drawings,

Figure 1 is a vertical central sectional view taken through my nut cracking machine with parts broken away,

Figure 2 is a top plan view thereof with parts illustrated in horizontal section,

Figure 3 is an elevational view of the receiving side of the rotor or centrifugal wheel,

Figure 4 is a vertical sectional view through the hub and mounting shaft thereof showing the opposite side of the rotor in elevation, and

Figure 5 is a perspective view of the rotor detached.

Referring more in detail to the drawings a rectangular base 10 is provided for the machine mounted upon legs 11 with a propelling shaft 12 journaled in bearings 13 upon the base 10 in a horizontal position, different sized pulleys 14 carried by the

shaft 12 being employed to revolve the shaft at different speeds by means of a belt such as 15.

A drum 16 herein illustrated substantially 60 pan-shaped is rigidly mounted adjacent the opposite ends of the shaft 12 with spiders 17 at each end of the shaft having the hubs 18 thereof secured to the shaft as by pins 19 and passing through central openings 20 65 in the closed inner sides 21 of the drum 16. A rotor or centrifugal wheel 22 is mounted in each drum 16 upon one of the spiders 17, the rotors consisting of a disk 23 with a hollow X-shaped member 24 upon one face 70 thereof providing hollow radial spokes 25.

The rotors 22 are secured to the spiders 17 by hold-fast devices such as bolts or rivets 26, the rotors 22 being revolvably mounted in this manner at the ends of the shaft 12 75 centrally of the drum 16. A central receiving opening 27 for the nuts to be operated upon is provided in the X-shaped member 24 of the rotor with a stationary conveying tube or pipe 28 leading to the entrance 27 of each rotor. The rapid rotation of the centrifugal wheels 22 simultaneously with the feeding of nuts through the pipes 28 and openings 27 forcibly throws the nuts outwardly by centrifugal action against the 80 oblique outer walls or rims 29 of the drums 16. The violent striking of the nuts against the walls 29 breaks and removes the husk and upon increasing the velocity of rotation of the rotors 22, the force of the blow is increased for cracking the nuts.

A cover or plate 30 at the open side of each drum 16 guides the nuts after being operated upon downwardly through the open bottom 31 of the cover. The angular 85 position of the sides 29 of the drum 16 prevents the nuts from bounding back against the rotors 22 and causes the nuts to bound outwardly toward the outlet covers 30. It will be apparent that the force with which 100 the nuts are thrown against the cracking sides or walls 29 of the drums 16 is regulated by controlling the speed of rotation of the shaft 12 as propelled by the belt 15 running over the pulleys 14. The 105 complete operation of the invention will be apparent from this detail description thereof, the machine being capable of husking as well as cracking large quantities of nuts in an expeditious 110 manner, it being noted that the inlet pipes 28 are fixed through perforations 32 in the

covers 30. While a form of machine is herein set forth for purposes of illustration it will be understood that minor changes may be made therein without departing from the spirit and scope of the invention.

What is claimed as new is:—

1. In a device of the character described a support, a horizontal shaft journaled thereon, means for varying the speed of said shaft, a spider fixed to one end of said shaft, a disc secured to said spider, hollow radial spokes fixed to said disc and communicating at their adjacent ends, a drum enclosing the end of said shaft, said drum comprising a closed inner side, an oblique outer rim formed with said inner side, and a cover plate having a discharge opening formed with said rim, said cover plate further having an aperture, and a feeding tube positioned in said aperture and terminating within the communicating space for said hollow spokes to discharge therein.
2. In a device of the character described, a support, a horizontal shaft journaled thereon, means for driving said shaft, a spider fixed to one end of said shaft, a disc secured to said spider, hollow radial spokes

fixed to said disc and communicating at their adjacent ends, a drum enclosing the spider, disc, and radial spokes, said drum comprising an imperforate inner side interposed between said disc and support, an oblique outer rim formed with said inner side extending axially outwardly from said support and driving means, a cover plate formed with the oblique outer rim, said cover plate having an opening adapted for discharging the separated shells and kernels longitudinally from the end of the entire device away from said support and driving means and a feeding tube terminating at its inner end within the communicating space for said hollow spokes passing through said cover plate from the end of the device in vertical alinement with the discharge opening whereby an operator of the apparatus may handle both the feeding and discharging of nuts without changing his position and while in a safe position from the driving means.

In testimony whereof I affix my signature.

MAXWELL RIDDELL.
